[75] Inventor: Kent E. Iversen, Columbus, Ohio

Primary Examiner—A. Hugo Word

Assistant Examiner—Stella M. Reid

[73] Assignee: Abbott Laboratories, Abbott Park,
Ill.

Attorney, Agent, or Firm—Donald O. Nickey; E. H.
Gorman, Jr.; Martin Katz

[**] Term: 14 Years

[57] CLAIM

[21] Appl. No.: 118,685

The ornamental design for a Y-connector or similar
article for enteral feeding tubes, as shown and de-
scribed.

[22] Filed: Nov. 6, 1987

DESCRIPTION

[52] U.S. Cl. D24/53

FIG. 1 is a front elevational view of a Y-connector or
similar article for enteral feeding tubes showing my new
design with the two entry ports uncapped;

[58] Field of Search D24/53; 604/165, 167,
604/96, 103, 256, 283, 250, 251, 54, 80, 82, 83,
281, 264, 270, 257; 128/658, 673

FIG. 2 is a top plan view thereof;

FIG. 3 is a right side elevational view thereof;

FIG. 4 is a left side elevational view thereof;

FIG. 5 is a bottom plan view thereof;

FIG. 6 is a rear elevational view thereof; and

FIG. 7 is a front elevational view similar to FIG. 1 but
with the two entry ports capped.
